UNITED STATES PATENT OFFICE.

CLYDE C. BALSTON, OF NEW YORK, N. Y., ASSIGNOR TO ANTHONY BARKER, OF NEW YORK, N. Y.

DUMB-BELL AND THE LIKE.

1,019,584.

Specification of Letters Patent.

Patented Mar. 5, 1912.

Application filed March 10, 1911. Serial No. 613,606.

To all whom it may concern:

Be it known that I, CLYDE C. BALSTON, a citizen of the United States, and resident of New York city, in the county of New York and State of New York, have invented certain new and useful Improvements in Dumb-Bells and the Like, of which the following is a specification.

My invention relates to improvements in dumb-bells, bar-bells, and the like, and has for its object to enable the ready altering of the weight of the device, and to enable the ready insertion into the bell of water, shot, or the like, as desired.

15 My invention comprises novel details of improvement and combinations of parts that will be more fully hereinafter set forth and then pointed out in the claims.

Reference is to be had to the accompanying drawings forming part hereof, wherein,

Figure 1 is a partly sectional side view of a dumb-bell or bar-bell embodying my invention, and Fig. 2 is a section on the line 2, 2, in Fig. 1.

25 The numeral 1 indicates a hollow bell or member shown provided with a flattened end 1^a, whereby it may readily stand to be charged. The hollow member 1 is provided with a threaded opening 2, and a funnel-like mouth 3 made conical on its inner surface 3^a. Member 1 is also provided with a seat 4 adjacent the inner portion of surface 3^a to receive a packing or gasket 5. The bar 6 is provided with external threads 7 adapted to engage threads 2, and said bar is also provided with a head 8 having a lower cone-like surface 9 to fit against the cone-like surface 3^a. Head 8 is shown provided with a threaded bore receiving the threads 7 of bar 6 so that said head may be screwed tight to the shoulder on bar 6 at 10. Head 8 has an end seat 11 to engage and press against gasket 5 to make a tight joint for the bell. At 12 is a screw passing through bores in bar 6 and head 8 and threaded in a portion of such bores so as to bear forcibly against the mouth 3 to retain bar 6 firmly set in position in connection with bell 1. Head 8 may be provided with

40 a nut-like portion 8^a to permit ready connection and disconnection of the parts.

In using the device screw 12 may be released from funnel-mouth 3, head 8 and bar 6 may then be unscrewed, and bell 1 may be charged with water, shot, or the like, to 55 provide the desired weight, and then bar 6 and head 8 will be screwed back into bell 1, so that head 8 will bear firmly against packing or gasket 5 to prevent leakage, and then screw 12 will be screwed firmly against funnel 3 to prevent disconnection of the parts. 60

The screw 12 may be screwed partly out or rearwardly, as indicated in dotted lines in Fig. 1, and will then serve as a handle to aid in rotating bar 6 and head 8 for applying them to or removing them from the bell. 65

While I have shown two bells 1 and a single bar 6, which may be of any suitable length, it will be understood that the parts 70 may be adapted for use as a dumb bell or bar-bell having double bells, or as a dumb-bell or club having a single bell.

Having now described my invention what I claim is:—

1. The combination of a hollow bell having a funnel-like mouth, with a bar provided with an enlarged head having a cone-like surface fitting said mouth, and means for retaining said bar in position. 75

2. The combination of a hollow bell having an opening provided with threads and having a funnel-like mouth exterior to said threads, with a bar having threads fitting the first named threads, and having an enlarged head having a cone-like surface fitting said mouth, and means to retain said bar in set position. 80

3. The combination of a hollow bell provided with a funnel-like mouth and a seat, a gasket for said seat, and a bar passing into said mouth and fitted to said bell, said bar having a head provided with a conical face engaging said mouth and gasket. 90

4. The combination of a hollow bell provided with a funnel-like mouth and a seat, a gasket for said seat, a bar passing into said mouth and fitted to said bell, said bar having a head engaging said mouth and gasket, and a screw passing through said 100 head to bear against said mouth.

5. The combination of a hollow bell pro-

vided with a mouth, a bar, means for securing said bar to said bell through said mouth, said bar having a head fitting said mouth, and a screw passing through said bar and 5 mouth and bearing against said mouth to retain the bar from rotation therein.

Signed at New York city, in the county

of New York and State of New York, this 6th day of March, A. D. 1911.

CLYDE C. BALSTON.
